Primary Examiner — Wendy L Arminio(74) *Attorney, Agent, or Firm* — ScienBiziP, P.C.(57) **CLAIM**

The ornamental design for a cup lid, as shown and described.

DESCRIPTION

FIG. 1 is a front, right and top perspective view of a cup lid, showing my new design in a position of use attached to an unclaimed cup drawn in broken lines.

FIG. 2 is a front elevation view thereof, with the cup lid shown removed from the cup.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is another perspective view of the cup lid of FIG. 1 shown in an alternative configuration with the lid switch in an open position.

The broken lines in FIGS. 1 and 8 illustrating a cup depict environmental structure and form no part of the claimed design. All other broken lines depict boundaries of the claim and form no part thereof.
